UNITED STATES PATENT OFFICE.

HOWARD GREER, JR., OF EVANSTON, ILLINOIS, ASSIGNOR TO CARTER H. FITZ-HUGH AND FREDERICK P. LUTHER, OF CHICAGO, ILLINOIS.

DUMPING-CAR.

1,101,177.

Specification of Letters Patent. Patented June 23, 1914.

Original application filed November 14, 1910, Serial No. 592,166. Divided and this application filed August 9, 1912. Serial No. 714,178.

To all whom it may concern:

Be it known that I, HOWARD GREER, Jr., a citizen of the United States, residing at Evanston, in the county of Cook and State 5 of Illinois, have invented certain new and useful Improvements in Dumping-Cars, of which the following is a specification.

This application is a division of my original application, Serial No. 592,166, filed in 10 the United States Patent Office on November 14, 1910, and to which application reference may be had for a full understanding of parts not specifically described herein.

The present invention relates in general 15 to dumping cars, and one of the objects of the invention is to provide an improved door construction whereby the doors will be reinforced and braced equally throughout their length.

20 A further object is to provide improved end structure for the car.

A further object is to provide an improved car of this character which will be simple, durable and cheap in construction, 25 and effective and efficient in operation.

To the attainment of these ends and the accomplishment of other new and useful objects, as will appear, the invention consists 30 in the features of novelty in substantially the construction, combination and arrangement of the several parts hereinafter more fully described and claimed and shown in the accompanying drawings exemplifying the invention, and in which—

35 Figure 1 is an end elevation of a car body constructed in accordance with the principles of this invention. Fig. 2 is an elevation of one-half of one of the side doors of a car. Fig. 3 is a sectional view on line 3—3,

40 Fig. 2. Fig. 4 is a detail view, partly in elevation and partly in section of the left hand end of the structure shown in Fig. 2 constructed in accordance with the principles of this invention, and showing a portion of 45 the car sills. Fig. 5 is a detail sectional view on line 5—5, Fig. 1. Fig. 6 is a top plan view of one of the side doors. Fig. 7 is an elevation of the center plate of one of the ends of the car. Fig. 8 is a sectional view on 50 line 8—8, Fig. 7, with parts in elevation. Fig. 9 is a rear view of the adjustable plates

shown in Fig. 7. Fig. 10 is a detail sectional view on line 10—10, Fig. 7. Fig. 11 is a detail sectional view on line 11—11, Fig. 7. Fig. 12 is a detail sectional view on line 55 12—12, Fig. 6. Fig. 13 is a sectional view on line 13—13, Fig. 6. Fig. 14 is a sectional view on line 14—14, Fig. 2.

The sills 34 of the car rest upon the truck bolsters (the latter not being shown) and 60 the car body 35 is supported by the sills 34 through the medium of pedestals 36 and the car body has a pivotal movement with respect to the pedestals, whereby the car may be dumped to one side or the other of the 65 truck.

The car body 35 is maintained against its dumping movement by means of chains 37 which latter may be of any ordinary and well-known construction. One extremity of 70 each of the chains is secured to the car body 35 and in order that this end may be readily detached from the car body when desired, a detachable fastening means, which will now be described, is provided. The bottom of the 75 car body may be braced by means of channel irons 38, any number of which may be provided, and the flanges 39 thereof are provided with registering apertures 40. A fastening pin or bolt 41 passes through registering apertures in the flanges 39 and also 80 through one of the links in the chain 37. The fastening pin is held against accidental displacement by means of cotter pins 42, which pass through each end of the fastening pin 41 and on the outside of the flanges 39. Thus, it will be seen that in the event 85 of the bending of the pin or bolt 41 either one or the other of the cotter pins 42 may be removed and the fastening pin or bolt 90 readily removed. The flanges 39 being spaced some distance from each other, the end of the chain 37 will be capable of movement between the flanges 39 and on the fastening pin or bolt 41 to permit the car to 95 travel around a curve which will cause the end of the chain to slide on the fastening pin or bolt 41 and thereby prevent wrenching or damaging of the parts. The other extremity of each of the chains 37 is secured to the 100 truck bolster in a manner which is not concerned in the present invention.

The doors constituting the side of the car body comprise members 46, which may be constructed of any suitable material, but preferably of wood, and each is of a length 5 to extend the entire length of the car. These members 46 are superposed with the edge of one member adjacent the edge of the other, and a substantially T shaped angle member having a web 47 and a body 48 is 10 arranged so that the web 47 will project between the adjacent edges of the members 46 and with its body 48 engaging and resting against one face of each of the members 46 and overlapping the edges thereof. The 15 body 48 of the T shaped member prevents the members 46 from buckling with respect to each other and is held in position by means of end plates or members 49 resting against the ends of the members 46 and the 20 adjacent portion of the face thereof. This end member 49 is provided with an offset portion 50 adapted to receive the body portion 48 of the T shaped member, as shown more clearly in Figs. 2 and 3. An angle 25 iron 51 is provided, which covers the inner upper edge of the door, as shown more clearly in Fig. 12, so as to protect the edge of the door against wear or damage which would be caused by falling articles, and a 30 similar angle iron 52 is arranged at the lower outer edge of the door so as to protect that edge thereof. A face plate 53 is secured to the inner face of the door and against which the members 46 rest. A 35 member 54, which may be constructed of any suitable material, preferably wood, is arranged to overlap the joint formed by the adjacent edges of the members 46 and the angle member therebetween. This member 40 54 is of a width to extend for some distance on both sides of the body member 48 and also extends for some distance on each side of the longitudinal center of the door. An angle bar or member 55 is provided adjacent each end of the member 54 and is of 45 a substantially L shaped formation. One of the flanges of the member 55 engages and extends across the end of the member 54 to project for some distance beyond the 50 outer face thereof. The other flange of this angle member 55 extends between the adjacent portion of the member 54 and the members 46. Another angle bar or member 56, similar in construction to the angle member 55, is also provided adjacent each end of the member 54 and this angle member 56 is disposed so that one of its flanges engages and rests against the outer face of the end member 54 and in proximity of the flange 60 of the angle member 55, which engages the end and extends beyond the outer face of the member 54. The other flange of the angle member 56 engages and rests against the last referred to flange of the angle member 55. These flanges or members 55

and 56 are respectively provided with apertures 57, 58 which register with each other and in which portions of truss rods or bars 59 are seated. One extremity of each of these truss rods or bars 59 projects into a 70 recess 60, which opens through the outer face of the members 46 and which is closed by the end plates 49. The extremities of the truss rods or bars project beyond the end plates 49 and are provided on their free 75 extremities with nuts or collars 61, which engage and rest against the portion of the end plates 49 which have engagement with the ends of the members 46.

Arranged in the longitudinal center of 80 the door thus formed and resting against the outer face of the member 54, is a center plate designated generally by the reference numeral 62, which latter is provided with rearwardly projecting flanges 63, 64 at the 85 top and bottom thereof, and which flanges engage over and rest upon the upper and lower edges of the member 54. This center plate 62 is also provided with spaced laterally projecting ears or lugs 65, each of 90 which is provided with an aperture therethrough and through each of which apertures one extremity of each of the truss rods or bars projects. The extremities of opposite truss rods or bars 59 terminate short of each other 95 and are preferably threaded as at 66 to receive nuts or collars 67, which latter are located between opposite ears or projections 65. It will thus be seen that the center plate 62 acts in the nature of a turn buckle, 100 by means of which the truss bars or rods 59 may be tightened. It will be apparent that a door constructed in this manner will be braced and reinforced throughout its entire length and that comparatively light material may be employed in its construction, while at the same time a door having a 105 maximum amount of strength will be produced.

The front and rear ends of the car body 110 are constructed in a similar manner and comprise two members 68, similar to the members 46, which are superposed in a similar manner and a reinforcing T shaped member is provided, the web 69 of which 115 projects between the adjacent extremities of the member 68, and the body 70 of which rests against the outer faces of these members.

In order to provide means whereby the front and rear ends of the car body may be 120 constructed of varying heights without necessitating the construction of a center plate of various sizes to meet the varying condition, the center plate is adjustably constructed and comprises two sections or members 125 71, 72 (see Figs. 7 to 9). One of these sections, the section 72, is provided with an offset portion 73 adjacent its center so as to extend longitudinally thereof, and the other section 71 is provided with a recessed por- 130

tion 74 adapted to receive the offset portion 73. One of these sections, preferably the section 72, is provided with elongated slots 75 adapted to receive bolts or fastening devices 76, which latter pass through apertures in the adjacent portions in the section 71 so that by loosening the fastening devices 76, the two sections may be adjusted longitudinally with respect to each other, and 5 when thus adjusted, the fastening devices may be again tightened to secure the parts in their adjusted positions with respect to each other. The section 71 is preferably provided with a flange 77 which is adapted 10 to extend over and rest upon the top edge of the upper member 68. The center plate thus formed may be secured in position in any suitable manner, preferably by means of fastening devices 78 passing through the 15 respective sections of the members 68.

The dumping links 79 are secured by one extremity to the section 71 of the center plate and by their other extremities to the respective side doors and additional links 80 20 are provided, which are connected to the other section 72 and one pair of the links 79.

In order to connect the ends of the links to the respective parts so that they may be readily detached, fastening pins or bolts 81, 30 similar in construction to the fastening pins or bolts 41 are provided. These fastening bolts comprise a pin which passes through the links and the adjacent member to which they are connected, and are themselves held 35 against displacement by means of cotter pins 82 which pass through the extremities of these fastening devices. It will thus be seen that the pins or fastening devices 81 may be removed or detached by removing either 40 one of the cotter pins 82.

What is claimed as new is:

1. A door for dumping cars and the like comprising a pair of superposed members arranged edge to edge, an angle member 45 disposed to project between the adjacent edges thereof and to engage the faces of the members beyond the edges, said angle member extending substantially the entire length of the first recited members, end members 50 having engagement with the ends of the first recited members and the extremities of the angle member, an additional member engaging the faces of the first recited members to break joint therewith and extending over 55 the said angle member; a center plate engaging the said additional member, and tie rods having engagement with the center plate and the respective end members.

2. A door for dumping cars and the like 60 comprising a pair of superposed members arranged edge to edge, an angle member disposed to project between the adjacent edges thereof and to engage the faces of the members beyond the edges, said angle member 65 extending substantially the entire length of

the first recited members, end members having engagement with the ends of the first recited members and the extremities of the angle member, an additional member engaging the faces of the first recited members to 70 break joint therewith and extending over the said angle member, a center plate engaging the said additional member, and tie rods having adjustable engagement with the center plate and the respective end members. 75

3. A door for dumping cars and the like comprising a pair of superposed members arranged edge to edge, an angle member disposed to project between the adjacent edges thereof and to engage the faces of the members beyond the edges, said angle member extending substantially the entire length of the first recited members, end members having engagement with the ends of the first recited members and the extremities of the angle member, an additional member engaging the faces of the first recited members to break joint therewith and extending over 80 the said angle member, said additional member terminating short of the ends of the first recited members, end members engaging the ends of the said additional member, a center plate secured to the latter substantially midway of its length, and tie rods engaging said center plate and the respective end members on each side thereof. 90

4. A door for dumping cars and the like, comprising a pair of superposed members arranged edge to edge, an angle member disposed to project between the adjacent edges thereof, and to engage the faces of the members beyond the edges, said angle member extending substantially the entire length of the first recited members, end members having engagement with the ends of the first recited members and the extremities of the angle member, an additional member engaging the faces of the first recited members to break joint therewith and extending over 100 the said angle member, said additional member terminating short of the ends of the first recited members, end members engaging the ends of the said additional member, a center plate secured to the latter substantially midway of its length, and tie rods engaging said center plate and the respective end members on each side thereof. 105

5. A door for dumping cars and the like, comprising a pair of superposed members arranged edge to edge, an angle member disposed to project between the adjacent edges thereof and to engage the faces of the members beyond the edges, said angle member extending substantially the entire length of the first recited members, end members having engagement with the ends of the first recited members and the extremities of the angle member, an additional mem- 110
115
120
125
130

ber engaging the faces of the first recited members to break joint therewith and extending over the said angle member, said additional member terminating short of the ends of the first recited members, end members engaging the ends of the said additional member, a center plate secured to the latter substantially midway of its length, and tie rods adjustably connected to the center plate and the respective first recited end members, the others of said end members having slots through which the respective tie rods pass.

6. A door for dumping cars and the like, comprising a pair of superposed members arranged edge to edge, an angle member disposed to project between the adjacent edges thereof and to engage the faces of the members beyond the said edges, said angle member extending substantially the entire length of the first recited members, end members engaging the ends of the first said members and extending across the extremities of the angle member, an additional member engaging the faces of the first said members and extending across the angle member to break joint with the first said members, said additional member terminating short of the ends of the latter, and members engaging the ends of the said additional member, and a center plate secured to the latter, tie rods engaging the center plate and the respective end members, and angle members engaging the upper inner and lower outer edges of the door.

7. A door for dumping cars and the like, comprising a pair of superposed members arranged edge to edge, an angle member disposed to project between the adjacent edges thereof and to engage the faces of the members beyond the said edges, said angle member extending substantially the entire length of the first recited members, end members engaging the ends of the first said members and being recessed to receive the extremities of the angle member, an additional member engaging the faces of the first said members and extending across the angle member to break joint with the first said members, said additional member terminating short of the ends of the latter, end members engaging the ends of the said additional member and a center plate secured to the latter, tie rods engaging the center plate and the respective end members, and angle members engaging the upper inner and lower outer edges of the door.

8. A door for dumping cars and the like, comprising a pair of superposed members arranged edge to edge, an angle member disposed to project between the adjacent edges thereof and to engage the faces of the members beyond the said edges, said angle member extending substantially the entire length of the first recited members, end members

engaging the ends of the first said members and extending across the extremities of the angle member, an additional member engaging the faces of the first said members and extending across the angle member to break joint with the first said members, said additional member terminating short of the ends of the latter, and being of a width less than the combined width of the first recited members, end members engaging the ends of the said additional member, a center plate secured to the face of the additional member and having flanges extending over the top and bottom edges thereof, and tie rods engaging the center plate and the respective end members.

9. A door for dumping cars and the like, comprising a pair of superposed members arranged edge to edge, an angle member disposed to project between the adjacent edges thereof and to engage the faces of the members beyond the said edges, said angle member extending substantially the entire length of the first recited members, end members engaging the ends of the first said members and extending across the extremities of the angle member, an additional member engaging the faces of the first said member and extending across the angle member to break joint with the first said members, said additional member terminating short of the ends of the latter, end members engaging the ends of the said additional member and a portion projecting beyond the outer face of the latter, the last recited portion being provided with open slots, a center plate secured midway of the length of the door, and tie rods engaging said center plate and the respective first recited end members and projecting through the slots in the respective intermediate end members.

10. A door for dumping cars and the like, comprising a pair of superposed members arranged edge to edge, an angle member disposed to project between the adjacent edges thereof and to engage the faces of the members beyond the said edges, said angle member extending substantially the entire length of the first recited members, end members engaging the ends of the first said members and extending across the extremities of the angle member, an additional member engaging the faces of the first said members, and extending across the angle member to break joint with the first said members, said additional member terminating short of the ends of the latter, end members engaging the ends of the said additional member, said end members comprising a portion extending between the faces of the first recited members and the additional member and a portion projecting beyond the outer face of the latter, the last recited portion being provided with open slots, a center plate secured midway of the length of the

door, and tie rods having adjustable engagement with the said center plate and also with the respective first recited end members and projecting through the slots in the respective intermediate end members.

5 In testimony whereof I have signed my name to this specification, in the presence of

two subscribing witnesses, on this 6 day of August A. D. 1912.
